UNITED STATES PATENT OFFICE.

WILLY ZEBROWSKI, OF BERLIN-NEUKOLLN, GERMANY, ASSIGNOR TO GENERAL ELECTRIC COMPANY, A CORPORATION OF NEW YORK.

TUNGSTEN ARC LAMP.

Application filed January 20, 1925, Serial No. 3,668, and in Germany March 13, 1924.

My invention relates to tungsten arc lamps and in part to means for starting the arc in such lamps.

In such lamps the method of ignition by contact between the electrodes has been employed only in connection with direct current because in such case it is possible to use an oxide or an oxide containing element as the cathode electrode inasmuch as the cathode from the standpoint of illumination is not of great importance.

When it is contemplated to use alternating current it becomes necessary that both electrodes should be of pure tungsten because each electrode alternately becomes the anode and the cathode and both participate vitally in the illumination. However, it is a difficult matter to draw an arc between two tungsten electrodes and particularly in a neutral atmosphere such as nitrogen. In the case of lamps using pure tungsten the ignition is sometimes obtained by using a temporary high voltage. Sometimes when the atmosphere is one of the rare gases the arc is started by means of a glow ignition. The use of high voltage of course requires special apparatus and the use of rare gases in consequence of the low arc voltage requires a series resistance which entails a constant loss. For this reason, the rare gas lamps, as compared with the nitrogen filled lamps, are less efficient and consequently less commercial.

The object of the invention is to provide means for establishing an arc between pure tungsten electrodes in a nitrogen atmosphere. It is also an object of my invention to use an oxide element for bridging the electrodes normally; it is also an object to separate the electrodes from the oxide body in a novel manner, namely, not simultaneously, but one after another, so that the arc is first formed between the oxide body and one of the electrodes and thereafter the arc is carried over to the second electrode, the second electrode having become heated in the meantime as a result of the formation of the first arc.

It will be understood that in thus establishing the arc, the electrodes are to be drawn off one after another from the intermediate piece. In one form of construction the intermediate piece may be drawn off slantingly so as to leave one of the electrodes at a time.

The two electrodes in one arrangement

may be maintained in contact normally with the oxide body by spring pressure so that as the oxide piece is drawn off, one of the electrodes follows the oxide body only for a short distance and then breaks while contact between the second electrode and the body persists for a somewhat longer distance before the second break takes place.

This construction possesses the advantage that the ignition is reliable and the lamp may be operated without difficulty in connection with either direct current or an alternating current.

The details of the invention are herein set forth and claimed reference being had to the accompanying drawing which shows the tungsten lamp of my invention in front view.

Referring more in detail to the drawing, it will be seen that the lamp comprises the usual glass enclosure *a*, the foot *b*, the leading in wires *c* and *d*, and the supporting stems *e* and *f* which support tungsten electrodes *g* and *h* respectively.

To the foot *b* there is fastened a supporting rod *i*, which supports the oxide element *k*, which latter may have any suitable shape, as, for example, the form of a disc. This oxide body may consist of a mixture of tungsten and thorium oxide. If desired, this oxide body may be given a coating of alkaline earth metal, such as barium azide. Normally the rod *i* maintains the element *k* against electrodes *g* and *h*. The supporting rod *i* is secured to a bimetallic strip *l*. Furthermore, in proximity of the bimetallic strip there is a resistance heating unit *m*, which is interposed between the stem *e* and the supporting rod *i*. Therefore, when the circuit is closed through the lamp, this element *m* becomes heated and heats in turn the bimetallic strip *l*. The supporting rods *e* and *f* of the two electrodes *g* and *h* are adjusted so that when the element *k* is withdrawn one of the electrodes follows the element *k* a longer distance than the other. Therefore, one of the electrodes breaks with the element *k*, before the second electrode breaks with the same element.

With the arrangement described, when the current is turned on through the lamp, the flow takes place through the electrodes *g* and *h*, by way of the plate *k* and the glow wire *m* is thereby brought to a heated condition with a result that the bimetallic struc-

- ture *l*, is heated in turn. The latter therefore, begins to bend and thereby causes the plate *k* to recede. The electrodes of course follow and shortly the electrode *g*, for example, breaks contact with the plate *k*. Therefore an arc is established between the ball *g* and the plate *k*. The result is that the ball becomes quite hot while the plate *k* and the electrode *h* also become considerably heated even to a red glow before it separates from the plate *k*. This separation takes place shortly after, due to the action of the bimetallic strip *l*. When the second electrode separates from the plate *k*, the arc 10 at once passes over to the second electrode *h* with a result that the arc continues in operation between the two tungsten electrodes *g* and *h* without the interposition of the plate *k*. When the current is turned off 20 from the lamp the elements cool and the plate *k* returns to its initial position bearing against the two electrodes ready for a repetition of action described when the current is turned on again.
- 25 While it is immaterial when alternating current is being used which electrode is connected to either side of the line that supplies the current, care should be had that when direct current is used the electrode *g*, the 30 first to separate from the element *k*, be connected to the line so as to serve as an anode while plate *k* and the second electrode *h* serve as cathode.
- When direct current is used, the new tungsten lamp ignites effectively by using a simple series resistance and a pressure from 110 to 220 volts. When the lamp is used in connection with alternating current, a satisfactory ignition can not be obtained by using a series resistance with a voltage as low as 110. The minimum voltage with which the lamp will operate satisfactorily is 150. However it has been found that if for the 40 series resistance a choke coil is substituted, the ignition may be obtained with a line voltage of 110 volts. The choke coil provides a novel means for enabling ignition to take place at a comparatively low line voltage.
- 50 The structure of the lamp may be modified in that bimetallic strips of different shapes or of different dimensions may be inserted in the supporting rods of the electrodes *g* and *h*, so that when the current is turned on, one electrode is caused to leave the intermediate element *k*, before the other, in this case the element *k*, is maintained stationary and the electrodes are the ones which are caused to move alone.
- 60 It is also possible that the bimetallic strips thus inserted into the supporting rods of the intermediate piece *k* can be made in such form as to effect a turning of the intermediate piece during the process of drawing away from the electrodes so that the inter-

mediate piece goes off slantingly, thereby remaining somewhat longer in contact with one of the electrodes than with the other.

Finally the movement of the intermediate piece can be effected by the action of an electrode magnet, which may be substituted for the bimetallic strip. The form of the intermediate piece and the manner in which it is fastened and the formation of the tungsten electrodes may obviously be varied. The intermediate piece may consist, for example, of iron, coated with a suitable material possessing high enough electronic emissivity such, for example, as barium.

It will be understood, therefore, that I do not wish to be limited to the specification embodiments illustrated and described inasmuch as, in view of the disclosure, the device may be varied without departing from the spirit of the invention or from the scope of the class contained herein.

What I claim as new and desire to secure by Letters Patent of the United States, is:

1. The method of establishing an arc between two refractory electrodes in an atmosphere of neutral gas, which consists in bridging the electrodes with an element of high electronic emissivity and producing a gap between one of the electrodes and the element to start the arc between the two, allowing the second electrode to remain in contact with the element after the arc is started until it becomes heated and thereafter separating the second electrode to set up the arc between the two electrodes directly and without the interposition of the element.

2. The method of establishing an arc between two tungsten electrodes in an atmosphere of nitrogen, which consists in bridging the electrodes with an element of high electronic emissivity and producing a gap between one of the electrodes and the element to start the arc between the two, allowing the second electrode to remain in contact with the element after the arc is started until it becomes heated and thereafter separating the second electrode to set up the arc between the two electrodes directly and without the interposition of the element.

3. In an arc lamp, a pair of electrodes of refractory material and enclosing envelope an atmosphere of neutral gas in the envelope and an element of high electronic emissivity bridging the two electrodes and a means for separating one of the electrodes and the element and thereafter separating the other electrode and the element, whereby an arc is first established between one of the electrodes and the element and thereafter between the two electrodes directly.

4. In an arc lamp, a pair of electrodes of tungsten and an enclosing envelope, an

atmosphere of nitrogen in the envelope and an element of high electronic emissivity bridging the two electrodes, and means comprising a bimetallic strip for separating one of the electrodes and the element, and thereafter separating the other electrode and the element, whereby an arc is first established between one of the electrodes and the element and thereafter between the two electrodes directly.

5. In an arc lamp, a pair of metallic electrodes, and a sealed enclosing envelope, an element of high electronic emissivity bridging the two electrodes and means for separating one of the electrodes and the element and for thereafter separating the other electrode and the element, whereby an arc is first established between one of the electrodes and the element, and thereafter between the two electrodes directly, said means comprising a thermally operated element and a heating element for heating the latter,

said heating element arranged to be in circuit with the arc, when the arc is established, whereby the bridging element is retained 25 out of engagement with the electrodes, while the arc is in operation.

6. The method of establishing an arc between two metallic electrodes in an atmosphere of neutral gas, which consists in bridging the electrodes with an element of high electronic emissivity and producing a gap between one of the electrodes and the element to start the arc between the two, allowing the second electrode to remain in 25 contact with the element after the arc is started until it becomes heated and thereafter separating the second electrode to set up the arc between the two electrodes directly and without the interruption of the 40 element.

In witness whereof, I have hereunto set my hand this 3rd day of January, 1925.

WILLY ZEBROWSKI

atmosphere of nitrogen in the envelope and an element of high electronic emissivity bridging the two electrodes, and means comprising a bimetallic strip for separating one of the electrodes and the element, and thereafter separating the other electrode and the element, whereby an arc is first established between one of the electrodes and the element and thereafter between the two electrodes directly.

5. In an arc lamp, a pair of metallic electrodes, and a sealed enclosing envelope, an element of high electronic emissivity bridging the two electrodes and means for separating one of the electrodes and the element and for thereafter separating the other electrode and the element, whereby an arc is first established between one of the electrodes and the element, and thereafter between the two electrodes directly, said means comprising a thermally operated element and a heating element for heating the latter,

said heating element arranged to be in circuit with the arc, when the arc is established, whereby the bridging element is retained 25 out of engagement with the electrodes, while the arc is in operation.

6. The method of establishing an arc between two metallic electrodes in an atmosphere of neutral gas, which consists in bridging the electrodes with an element of high electronic emissivity and producing a gap between one of the electrodes and the element to start the arc between the two, allowing the second electrode to remain in 30 contact with the element after the arc is started until it becomes heated and thereafter separating the second electrode to set up the arc between the two electrodes directly and without the interruption of the 35 element.

In witness whereof, I have hereunto set my hand this 3rd day of January, 1925.

WILLY ZEBROWSKI.

CERTIFICATE OF CORRECTION.

Patent No. 1,617,979.

Granted February 15, 1927, to

WILLY ZEBROWSKI.

It is hereby certified that error appears in the printed specification of the above numbered patent requiring correction as follows: Page 2, lines 104 to 117, strike out claim 2; same page, lines 118 and 129, and page 3, lines 11 and 28, for "3, 4, 5 and 6" read "2, 3, 4 and 5" respectively; and that the said Letters Patent should be read with these corrections therein that the same may conform to the record of the case in the Patent Office.

Signed and sealed this 22nd day of March, A. D. 1927.

Seal.

M. J. Moore,
Acting Commissioner of Patents.

CERTIFICATE OF CORRECTION.

Patent No. 1,617,979.

Granted February 15, 1927, to

WILLY ZEBROWSKI.

It is hereby certified that error appears in the printed specification of the above numbered patent requiring correction as follows: Page 2, lines 104 to 117, strike out claim 2; same page, lines 118 and 129, and page 3, lines 11 and 28, for "3, 4, 5 and 6" read "2, 3, 4 and 5" respectively; and that the said Letters Patent should be read with these corrections therein that the same may conform to the record of the case in the Patent Office.
